UNITED STATES PATENT OFFICE

ROBERT A. PHAIR, OF ALLENDALE, NEW JERSEY, AND BARTHOLOMEW BUCARIA, OF BROOKLYN, NEW YORK, ASSIGNORS TO H. KOHNSTAMM & CO., INC., OF NEW YORK, N. Y., A CORPORATION OF NEW YORK

LAUNDERING TEXTILE FABRIC

No Drawing.

Application filed March 6, 1925. Serial No. 13,455.

Laundering textile fabrics of which the following is a specification.

The invention aims to improve laundering operations on textile fabrics, and particularly the bleaching step in such operations, by mixing with the bleach certain porous material which removes oily matters by absorption and thus aids the bleach in the removal of stains. The mixture may be made before adding it to the water, and the porous material may be in such percentage as to make a solid or pasty compound which is more convenient and economical to handle than the liquid bleaches ordinarily used by laundries.

15 Various silicates, silicate compounds or substituted silicates may be used as the absorbent, and various bleaches as the absorbed liquid.

We prefer the special form of silica, variants of which go by the names of infusorial 20 earth, kieselguhr, diatomaceous earth, filter-cel, and so forth. The silica compound (in which term we include silicas of corresponding physical structure) absorbs the liquid bleach by reason of its porous structure.

25 The invention includes mixtures which are not entirely free from water and which may, for example, be pasty. The proportions will be varied depending on the characteristics of the particular infusorial earth in hand, its absorbent power, the degree of dryness desired in the product, and the percentage of available chlorine in the bleach used. For example, equal quantities may be used of infusorial earth and of a solution of hypochlorite

30 containing 12% available chlorine. With better quality of infusorial earth as little as about 30% of the total may be used. The maximum percentage of infusorial earth useable in laundry work is about 92%. The solid

35 bleach may be introduced directly in the wash water just as liquid bleaches are now used.

The earth or other insoluble silicate referred to serves an additional purpose in that it helps to emulsify oils, fats and grease in the

40 fabrics during the laundering operations. This is true even though the character and quantity of the silicate are not such as to produce a dry mixture and the invention is its broadest aspect includes a mixture with the

45 bleach of a substantial percentage of the sili-

cate so as to increase the efficiency of the bleach. The emulsification of the fats and waxes by the silica compound, aids the bleaching operation very greatly by removing from any stains in the fabric the waterproof covering. This aids very greatly in the removal of a large number of colored and grease stains and aids very greatly in the efficiency of the bleach.

55 It is an important consideration in making a commercial product that an infusorial earth or other insoluble silicate be used from which all or practically all of the common organic matters have been eliminated. Otherwise such matters tend to decompose the bleach 60 and to render the mixture unsuitable and valueless after it becomes old. For the same reason it is important to purify the earth by removing any impurities which may be present, such, for example, as iron. The most 65 common impurities are organic matter and iron, and these particularly should be entirely or nearly eliminated.

70 For the greatest stability the bleach also should be free from iron, nickel, copper and other catalytic agents. These catalytic agents often times contaminate the bleach from the containers and utensils used.

75 The bleach and silicate may be used without previous admixture. That is, they may 80 be added separately to the water in the bleaching stage of the laundering operation.

What we claim is:

1. In the laundering of textile fabrics the improvement which consists in adding to the 85 water during the bleaching operation a mixture of a bleach and a silica compound of porous structure which removes oily matters in the fabrics by absorption and thus aids the bleach in removing stains and which is 90 carried off in the laundering operation.

2. In the laundering of textile fabrics the bleaching method which consists in the removal of oily matters in the fabrics by the 95 addition to the wash water of a silica compound of porous structure which absorbs such oily matters and a bleach which removes stains from which the oily matters have been removed.

3. The method of claim 2, using a silica 100

compound which has first been freed of organic and other impurities which tend to decompose or contaminate the bleach.

4. The method of claim 2, the additions consisting of the silica compound to the extent of about thirty to fifty per cent and a solution of hypochlorite.

In witness whereof we have hereunto signed our names.

ROBERT A. PHAIR.
